UNITED STATES PATENT OFFICE.

CHARLES F. SPLITDORF, OF NEW YORK, N. Y.

CONTACT-BREAKER.

SPECIFICATION forming part of Letters Patent No. 728,632, dated May 19, 1903.

Application filed September 19, 1902. Serial No. 123,996. (No model.)

To all whom it may concern:

Be it known that I, CHARLES F. SPLITDORF, a citizen of the United States, residing at New York, in the county and State of New York, have invented new and useful Improvements 5 in Contact-Breakers, of which the following is a specification.

This invention relates to contact-breakers for induction-coils; and it comprises in particular certain novel means permitting the delicate and positive adjustment of the armature-spring, whereby its degree of tension may be regulated with exactness without liability to change unless manipulated, and thus 15 the desired speed of vibration is assured.

A further feature of my invention lies in the extreme simplicity of the several parts employed and the ease and rapidity with which the armature-spring adjustment and 20 its positive locking may be effected.

In the drawings accompanying this application, Figure 1 is an end view of a coil-casing having mounted thereon my improved contact-breaker. Fig. 2 is a side section 25 thereof. Fig. 3 is an end view of a case containing several coils and showing a modified form of adjusting device more conveniently arranged for manipulation. Fig. 4 is a side section thereof. Fig. 5 is a front elevation 30 of my contact-breaker. Fig. 6 is a side view thereof with section of casing. Fig. 7 is a rear elevation thereof. Fig. 8 is a front elevation of the contact-breaker having a modified form of adjustment. Fig. 9 is a side 35 view thereof with section of casing. Fig. 10 is a rear elevation. Fig. 11 is an enlarged detail view of the adjusting-screw. Figs. 12 and 13 are enlarged detail views of the armature-spring.

In the figures, A indicates a coil-casing; B, a base or support for a spring C, which latter is secured thereto at one end, as by screws b, said spring carrying an armature D at its opposite end. Said base is secured to the casing in any desired manner, as by screws d.

E indicates the usual platinum tip, located at the rear of armature D and adapted to contact with a platinum tip, as F, that is located at the end of an adjusting-screw, as G. This 50 screw G is threaded through a slot h in bridge H, mounted upon the casing A, and is securely held within the slot h by a tightening-

screw h'. The slot h in bridge H is provided about centrally of its length with a threaded passage for the reception of the contact-point-adjusting screw G, which latter by turning its knurled head may be regulated to adjust the distance desired between the platinum points E F.

While I may use only one tightening-screw, 60 as h', I prefer to employ two, one at each side of the screw G. These screws h' are screwed transversely through the bridge H and tightened to contract the divided members thereof and bind them upon screw G to 65 secure the latter in place. The bridge is secured to the coil-casing by screws g², passed through threaded passages formed one at each end within the slot h.

The support B is provided with an extension, as I, that lies beneath the spring C, in an approximately parallel plane therewith when said spring is without tension. Said extension I is in the manner of a tongue and is provided toward its free end with a slot, 75 which in the form of my invention shown in Figs. 1, 2, 5, 6, and 7 lies in a plane parallel with the sides of the tongue I, the slot being indicated by the letter i. A threaded orifice i' is formed intermediate the slot-divided 80 tongue members, and the threaded portion j of an adjustment-screw J is introduced therein. The screw J has reduced portion j', bounded by the upper end of the thread j, and an enlarged shoulder portion j², and said reduced 85 portion j' is adapted to be loosely contained within the contracted extension k of a slot K, formed in the spring C and located in alignment with the threaded orifice i'. In advance of the orifice i' near the open end of slot i, but 90 at right angles thereto, another threaded orifice L is provided, and a screw l is introduced therein, uniting the two tongue members over the slot and binding them tightly over the screw J to lock the latter to its adjusted position. Because with the arrangement of lock-screw l it would be difficult to apply a screw-driver to one of several such devices when attached in a row to a coil-casing containing several coils I have, as seen in Figs. 100 3, 4, 8, 9, and 10, formed the slot (indicated by the letter M) in a plane parallel with the front and rear surfaces of the tongue I; also, with this form of slotted tongue the screw-

orifice, as *m*, passes through the tongue at right angles to the slot, and a further screw-orifice *m'* to receive the lock-screw *l'* is formed parallel with orifice *m*. The slot in spring C for this modified form is elongated to permit the exposure of screw *l'* therethrough and to enable a screw-driver to be applied thereto.

As will be clearly perceived from the foregoing description, the armature-spring C, which is secured to the support B by screws *b*, can by loosening the lock-screw *l'* be readily and accurately adjusted to any desired degree of tension by turning the screw J and the speed of vibration thus determined, and, further, that in tightening up the screw *l* or *l'* the position of the vibrator is set or locked without the slightest deviation ensuing from the act of binding or locking it. It will also be evident that whereas the laterally-arranged lock-screw *l* is very convenient and serviceable where only one or two contact-breakers are mounted side by side upon a coil-casing, yet when three or more contact-

breakers are arranged in line upon a coil-casing the locking-screws of the intermediate devices could not be conveniently operated by a screw-driver if arranged laterally, whereas the lock-screw, as *l'*, is in position to be operated from the front of the device.

I claim—

In a contact-breaker, a vibrator-spring carrying an armature and contact-point, a support for said spring, a slotted body, a screw member having a narrowed portion, a slot in the vibrator-spring to receive said narrowed screw portion, a threaded orifice in the slotted body to receive the screw member, and a lock-screw threaded through the slotted body to contract its members.

In testimony whereof I have hereunto set my hand in the presence of two subscribing witnesses.

C. F. SPLITDORF.
